UNITED STATES PATENT OFFICE.

OTIS A. MYGATT, OF NEW YORK, N. Y.

DESIGN FOR A PRISMATIC-GLASS REFLECTOR.

No. 38,006.

Specification for Design.

Patented May 8, 1906.

Application filed August 1, 1905. Serial No. 272,263. Term of patent 14 years.

To all whom it may concern:

Be it known that I, OTIS A. MYGATT, a citizen of the United States, residing at New York, in the county of New York and State of New York, have invented a certain new, original, and ornamental Design for a Prismatic-Glass Reflector, of which the following is a specification, reference being had therein to the accompanying drawings, forming part thereof.

The reflector is composed of clear glass.

Figure 1 is a side elevation, and Fig. 2 a bottom perspective.

The full lines, Figs. 1 and 2, are intended to indicate external reflecting-prisms, and the dotted lines, Fig. 2, indicate that such prisms are visible on the interior of the reflector.

I claim—

The ornamental design for a prismatic-glass reflector of the form shown, having external reflecting-prisms visible on the interior as shown and described.

OTIS A. MYGATT.
